C. A. HOXIE

VARIABLE CURRENT GENERATOR

Filed May 20, 1921

FIG. 1.

FIG. 2.

Inventor:
Charles A. Hoxie,
by *Albert G. Davis*
His Attorney.

Patented Nov. 27, 1923.

UNITED STATES PATENT OFFICE.

CHARLES A. HOXIE, OF SCHENECTADY, NEW YORK, ASSIGNOR TO GENERAL ELECTRIC COMPANY, A CORPORATION OF NEW YORK.

VARIABLE-CURRENT GENERATOR.

Application filed May 20, 1921. Serial No. 471,230.

To all whom it may concern:

Be it known that I, CHARLES A. HOXIE, a citizen of the United States, residing at Schenectady, in the county of Schenectady, State of New York, have invented certain new and useful Improvements in Variable-Current Generators, of which the following is a specification.

This invention relates to a method and apparatus for producing varying currents or voltages and is particularly applicable to the production of alternating or pulsating currents or voltages having any desired wave form.

One object of my invention is to provide an apparatus of this type wherein the amount of current or voltage produced at any instant is controlled by a screen placed in the path of light traveling from a suitable source to a photo-electric cell. This screen is provided with specially formed cut-way or transparent portions and is arranged to be moved so that the light which passes through these portions and falls upon the photo-electric cell is caused to vary in a manner corresponding to the variation which it is desired to produce in the current or voltage.

The preferred form of the apparatus constructed in accordance with my invention is particularly adapted for the production of currents or voltages which vary through periodic cycles and it may thus be used for the production of current or voltages of pure sine waves. Means are also provided whereby the frequency as well as the form of such waves may be changed as desired.

Other objects and advantages of my invention will appear from the following description taken in connection with the accompanying drawings, wherein Fig. 1 is a diagrammatic view of an apparatus constructed in accordance with my invention, and Fig. 2 is a showing in detail of means for controlling the passage of light to the photo-electric cell so that currents of sine wave form are produced.

Referring to Fig. 1 of the drawing, A represents a source of light, B a photo-electric cell and C a thermionic vacuum tube amplifier. Light from the source A passes through a lens 10, openings in the disc 11 and screen 12 hereinafter more fully to be described and thence to the cell B.

This cell may be conveniently made by

exhausting a tube and evaporating within the same a quantity of metallic potassium which is condensed upon the walls, a suitable barrier being provided to prevent its condensation over the surface which is intended to act as a window. 100 microns of hydrogen are then admitted to the tube and the light sensitive potassium tube is "formed" by connecting the tube in series with a resistance of about 10,000 ohms to a 65 500 volt source of potential which will pass about 33 milli-amperes through the tube in the form of a bluish discharge. In this operation the potassium constitutes the cathode. The result produced is an increase in 70 the sensitiveness of the tube. If desired the sensitiveness may be still further increased by introducing new hydrogen and again submitting the tube to discharge. Finally the 75 hydrogen is removed and argon gas is admitted, the pressure of this varying according to working conditions from 12 to 200 microns. Lower pressures are used with higher increases in potentials to give the tube a greater stability. Such a tube may 80 be conveniently operated at a potential which is between 50 and 500 volts. If desired to increase the sensitivity more argon may be admitted.

When this cell is placed in series with a suitable source of potential the current through the cell is dependent upon the quantity of light falling upon the cathode or the area of cathode surface illuminated. While I have shown and described one form of 85 photo-electric cell, it is clear that other forms may be used. I intend that the term "photo-electric cell" shall apply to a device of this type which is adapted to be included in an electric circuit and has the property 90 of changing the current passing therethrough in proportion to any change in the quantity of area of illumination to which the cell is subjected regardless of the rapidity with which the change in illumination is 95 effected. The cell I employ should be also substantially free from inductance or capacity. The screen in the form of invention shown in Fig. 2 is provided with an opening 14 to permit passage of light into the 100 cell B. The shape of this opening varies with the form of wave it is desired to produce and in the present instance is of a form to give a sine wave. The right and left edges of the openings are each of the form 110

of a sine curve. The disc 11 likewise interposed in the path of light from the source A to the cell B is mounted to rotate about an axis 15 and is adapted to be actuated by a motor 16 which may be controlled to run at any desired speed. The disc 11 in the form shown is provided with a series of openings 17 near its outer edge which are approximately rectangular in form and are spaced apart from one another by a distance equal to the width of an opening.

The effect of the rotation of the disc 11 in front of the opening 14 is to cause a beam of light of the form in cross section of one of the openings 17 to pass across the opening 14 at a uniform rate producing a definite variation in the quantity of light entering the cell and a resulting proportional variation in the current through the cell. In the form shown I have provided a rectangular opening in the disc 11 and a curved opening in the screen 12. The same results would, however, be effected by making the opening in the screen rectangular and the openings in the disc of the special form to give the desired wave. In connection with the form of openings in the disc and screen it is to be noted that the desired wave form is determined merely by the quantity of light which enters the cell B from instant to instant. It will thus be seen that various forms of openings will effect this result, the sole condition being that the change in area per unit distance in the direction of motion be the same. While I have shown the disc 11 provided with openings 17 as a means for causing the light to pass over the opening 14 it is obvious however that other means may be employed, such for example as a rotating mirror.

The circuit through the cell B includes a battery 18 and a non-inductive resistance 19, this circuit being in electrical connection with the grid 20 of the amplifier C from a point 21 intermediate the resistance 19 and anode 8. The filament 22 is connected to the opposite end of resistance 19 preferably through a few battery cells 23 to maintain a proper difference of potential between the filament and grid. In certain cases the potential difference across the terminals of the resistance 19 will be such as to make the use of these battery cells unnecessary. Included in the plate circuit of the amplifier is a source of current and a non-inductive resistance 24 to the ends of which are connected the terminals 25 and 26. While I have shown as an amplifier a pliotron, it is obvious that other forms of amplifiers may be used, such for example, as a dynatron. In any such case the photo-electric cell will be arranged so as to affect the control circuit of the amplifier.

From the above it will be seen that in operation a pulsating voltage of the desired

wave form is produced across the terminals 25 and 26. If it is desired to produce an alternating instead of a pulsating current or voltage, the primary of an air core transformer may be substituted for the resistance 24, the terminals 25 and 26 being connected to the secondary.

Prominent among the features of my device which contribute to the production of the voltage or current of a form in strict accordance with the shape of the light controlling openings is the use of a photo-electric cell which produces changes in current corresponding strictly to changes in the area illuminated and the use of electric circuits without appreciable inductance or capacity. Because of the latter feature my device may be employed without danger of interference to neighboring instruments because of stray magnetic or electrostatic fields.

What I claim as new and desire to secure by Letters Patent of the United States is:

1. The method of producing voltage or current waves of predetermined form by means of a photo-electric device having a light sensitive cathode which consists in causing the cross sectional area of a beam of light directed on said cathode to undergo variations corresponding to complete cycles of the desired voltage or current waves.

2. The method of producing voltage or current waves of predetermined form by means of a photo-electric device having a light sensitive cathode which consists in directing a beam of light upon said cathode, causing the beam to undergo cycles of variations in cross sectional area corresponding to complete cycles of the voltage or current wave desired, and amplifying said waves.

3. In a device for producing voltage or current waves having a predetermined definite form, the combination of a photo-electric device, means for directing a beam of light toward said device, and means comprising a pair of cooperating relatively movable members for varying the cross sectional area of said beam in accordance with the form of the waves to be produced.

4. In a device for producing voltage or current waves having a predetermined definite form, the combination of a photo-electric device, means for directing a beam of light toward said device, and a pair of relatively movable members arranged in the path of said beam, said members having registerable openings for varying the cross sectional area of said beam in accordance with the desired form of wave to be produced.

5. A device for producing periodic voltage or current waves having a definite predetermined form comprising a photo-electric device having a light sensitive cathode, a circuit including a source of energy con-

nected to said device, a source of light, means for directing a beam of light from said source onto said cathode, a screen and a rotatable disk each arranged in the path of 5 said beam of light, said disk having a plurality of substantially rectangular openings therein and said screen having an opening constructed to cooperate with each open-

ing in said disk to permit the passage of said beam and to vary the cross sectional area thereof in proportion to the amplitude of the instantaneous values of the voltage or current waves to be produced.

In witness whereof I have hereunto set my hand this 18th day of May, 1921.

CHARLES A. HOXIE.
